UNITED STATES PATENT OFFICE.

THOMAS J. KEHOE, OF TOLEDO, OHIO, ASSIGNOR TO THE WILLYS-OVERLAND COMPANY, OF TOLEDO, OHIO.

MOTOR-VEHICLE HOOD.

1,282,233.

Specification of Letters Patent. Patented Oct. 22, 1918.

Application filed December 4, 1915. Serial No. 64,970.

To all whom it may concern:

Be it known that I, THOMAS J. KEHOE, a citizen of the United States of America, residing at Toledo, Lucas county, Ohio, have 5 invented new and useful Motor-Vehicle Hoods, of which the following is a specification.

This invention relates to housings and particularly to motor vehicle hoods and 10 means for hinging the parts of the hood together.

One object of this invention is to provide a central hood hinge which may be constructed with the use of less material than is 15 now commonly used, so that hoods equipped with this hinge member may be more economically produced. Another object of my invention is to provide a central hood hinge which presents a substantially continuous 20 upper surface exposed to the weather so as to make the hood more attractive in appearance, and so as to shed water from the hinge and prevent its penetrating through the hinge joint to the interior of the hood so as 25 to interfere with the operation of the hinge or the motor.

Referring to the drawings:

Figure 1 is a perspective view of a portion of a motor vehicle having the hood 30 thereof embodying the invention herein;

Fig. 2 is a fragmentary view of the hood center hinge of Fig. 1 on an enlarged scale;

Fig. 3 is an end view, with one side of the hood elevated, of the hinge as shown in 35 Fig. 2;

Fig. 4 is a section on the line IV—IV of Fig. 2; and

Fig. 5 is a section on the line V—V of Fig. 2.

40 The vehicle 1 is provided with the hood having the top members 2 and 3, the upper edges of which are hingedly connected together at the center of the hood. The member 2 is provided at its central edge with a cylindrical bead 4 which forms the outer seat for the half round bead 5, which is integrally formed on the central abutting edge of the other hood section 3. The bead 4 is provided with a plurality of spaced notches 45 or recesses 7, which may extend from the free edge of the bead to about the center thereof or any desired distance from said free edge, and the hood section 3 has a plurality of curved tongues 6 which extend or project 50 from the free edge of the bead 5 and are rolled to form a substantially cylindrical

bead corresponding to the bead 4. These tongues 6 are so placed apart as to aline with the recesses 7 so that when the hood sections are assembled, the half round bead 5 fits 60 within and is embraced by the bead 4 on hood section 2, while the tongues 6 fit within the notches 7 to prevent a lateral shifting of the hood sections relative to each other. Locking pivot pins 8, having enlarged ends 65 9 for anchoring the hood in position over the motor, are inserted within the cylindrical bead formed by the curved tongues 6 and extend past the tongues 6 to within the bead 4.

70 This construction provides a central hood hinge having a substantially continuous and unbroken surface of an attractive appearance and in which the working parts of the hinge are not exposed, and which will shed 75 water and prevent its penetrating through the hinge joint to the interior of the motor or corroding the parts of the hinge so as to interfere with their operation.

I am aware that the embodiment of my 80 invention here shown and described is susceptible of considerable variation without departing from the spirit thereof, and therefore I desire to claim the same broadly, as indicated by the appended claims. I have 85 found, however, that this particular embodiment is desirable from many standpoints and, therefore, I wish to claim the same specifically as well as broadly.

What is claimed and it is desired to secure 90 by Letters Patent is:

1. The combination in a motor vehicle hood of a pair of hood sections, one of said sections being provided with an integral substantially cylindrical bead formed along 95 one edge thereof, said bead being provided with a plurality of spaced notches therein, the other of said hood sections being provided with a continuous half round bead formed along the abutting edge thereof, and 100 having a plurality of curved tongues in line with said notches and rolled upon themselves to form cylindrical beads, and locking pins extending through the beads, formed by said curved tongues into the cylindrical bead on 105 the first mentioned hood section.

2. In a motor vehicle hood, the combination of hood sections provided with a cylindrical bead on one of said sections, and a half round bead on the other of said sections 110 nested within said cylindrical bead and having a plurality of curved tongues extending

therefrom and coacting with said cylindrical bead to prevent lateral shifting of the hood sections and a pintle disposed in said cylindrical bead and embraced by said curved 5 tongues.

3. The combination of a pair of housing members to be hinged together, one of said members having a substantially cylindrical integral bead extending along one edge 10 thereof and provided with a notch extending from the free edge of said bead toward the center thereof, the other of said members having a half round bead nested in and embraced by said first mentioned bead and provided 15 with a tongue rolled upon itself to form a substantially cylindrical bead, and disposed in said notch, and a pintle embraced by said first mentioned cylindrical bead and said tongue.
- 20 4. In a motor vehicle hood, the combination of a pair of hood sections to be hinged together, the abutting edges of each hood section being formed with a continuous integral bead, one of said beads being nested 25 within the other, and the abutting edges of each hood section being provided with engaging means to prevent lateral shifting of

said hood sections relative to each other; and a pintle embraced by and engaging each of said beads.

5. In a motor vehicle hood, the combination of a pair of hood sections to be hinged together, each hood section being provided with a continuous integral bead on one edge thereof, the beads on said hood sections being nested one within the other, and said beads being provided with tongues and recesses respectively, coöperating to prevent lateral shifting of said hood sections relative to each other; and a pintle embraced by and 35 engaging each of said beads.

6. In a motor vehicle, the combination with a body of a pintle carried thereby; and a hood, including a pair of hood sections, each provided with a continuous integral 40 bead formed on one edge thereof, said beads being nested one within the other; and each hood section being provided with engaging means to prevent lateral shifting thereof, said pintle being embraced by and engaging 45 each of said beads.

In witness whereof I affix my signature.

THOMAS J. KEHOE.
